UNITED STATES PATENT OFFICE.

OSCAR H. BOHM AND WALTER M. MCCOY, OF BIRMINGHAM, ALABAMA.

JIGGING-MACHINE.

1,091,035.

Specification of Letters Patent. Patented Mar. 24, 1914.

Application filed April 9, 1913. Serial No. 759,901.

To all whom it may concern:

Be it known that we, OSCAR H. BOHM and WALTER M. MCCOY, citizens of the United States, and residents of Birmingham, in the county of Jefferson and State of Alabama, have made certain new and useful Improvements in Jigging-Machines, of which the following is a specification.

Our invention relates to improvements in the water controlling means and oiling means of jigging machines and other similar types of machinery, and it consists in the combinations, constructions, and arrangements herein described and claimed.

15 An object of our invention is to provide a device in which the working parts of the plunger reciprocating mechanism are submerged in oil so as to provide a thorough and constant lubrication, and which protects 20 the lubricating oil against contamination by grit, water, or other foreign substances.

A further object of our invention is to provide a device for holding the oil so that there is no escape for the latter, thereby rendering the oiling of the device far more economical than in the ordinary machine.

A further important object of our invention is to so design the plunger that the bottom opening valves which control the ports 30 in the plunger can be taken out through the plunger without necessitating the removal of the latter.

A further object of our invention is to provide the underface of the plunger with 35 a central countersunk recess or chamber surrounded by ported walls set at an angle to the horizontal bottom plane of the plunger and provided with a plurality of inwardly opening valves which close the ports on the 40 down stroke of the plunger. This arrangement enables the valves to be set so that no counter-weights or other auxiliary means are necessary to insure their prompt closing, and it also places them in the position where 45 they operate in the cleanest water and are subject to a minimum wear.

A further object of our invention is to provide a novel form of valve or door in the plunger which prevents accumulation 50 of water beyond that which is desirable inside of the plunger and also simplifies the construction and reduces wear on the parts.

A further object of our invention is to provide a novel form of valve and plunger 55 which is more positive in action, and by

means of which the back suction affecting material on the jigging sieve is practically eliminated.

Other objects and advantages will appear in the following specification and the novel features of the device will be particularly pointed out in the appended claims.

Our invention is illustrated in the accompanying drawings forming part of this application in which—

Figure 1 is a plan view of our invention as applied to a jigging machine, Fig. 2 is an enlarged section through the plunger and eccentric, Fig. 3 is an enlarged detail view showing the means of clamping the packing ring, Fig. 4 is a sectional view of the eccentric casing approximately on the line 4—4 of Fig. 2, the eccentric, Fig. 5 is an enlarged detail view of a modified form of pivotal bearing for the wrist pin, Fig. 6 is a section along the line 6—6 of Fig. 2, Fig. 7 is a section along the line 7—7 of Fig. 2, looking in the direction of the arrows, Fig. 8 is a sectional view through a modified form of the eccentric casing. Fig. 9 is a face view of one of the swinging flap valves, and Fig. 10 is a vertical section through the jigging machine.

Our invention may be applied to machines of various types. In the present instance 85 we have applied the invention to a jigging machine. We have shown only enough of the jigging machine proper to give a clear understanding of the application of our invention.

Referring to Fig. 1 it will be seen that we have provided on the frame 1 of the machine, bearings 2 for the drive shafts 3. In Fig. 1 we have illustrated two of these jigging machines and a description of the 95 novel means of one will suffice since they are both alike. The drive shaft 3 is provided with a loose pulley 4 and a fast pulley 5. Any suitable reciprocating means may be employed to operate the plunger from the 100 drive shaft 3. We have shown what we consider as our preferred means in Fig. 2, where the shaft 3 is shown keyed to the hub 6 of the eccentric ring 7. On the exterior of the latter is the adjusting member 8. The ring bears a series of notches 7^x so arranged that they may be brought into registration with adjacent notches 8^x on the 105 adjusting member 8 and may be held by means of a key 9. By unloosening the bolt 110

9^x (see Fig. 6) and removing the key 9 the position of the adjusting member 8 with respect to the eccentric ring 7 may be adjusted so as to vary the eccentricity of the device. In order to do this it is only necessary to bring two of the other registering recesses 7^x and 8^x into alinement and to again insert the key 9.

On the outside of the adjusting member 8 is the eccentric strap 10 which is clamped on the member 8 by means of the bolts 11. Secured to the frame 1 is a rectangular frame 12 to which is secured a frame 13 (see Figs. 2 and 7) having an integral cylindrical extension 13^x. The plunger consists of a cylindrical member 14 (see Figs. 2 and 7) which is arranged to slide on the inside of the cylinder 13^x. The member 14 bears an integral bottom frame work 14^x 20 which has at its center an oil receptacle 14^y.

The plunger 14 is designed to provide ported walls which are inclined at an angle to the horizontal bottom plane of the plunger and to this end the plunger has a central chamber or cavity which opens below and is surrounded by walls each of which is provided with a port 14^z. Each port 14^z is shown closed by a valve 15 which is hinged to a frame 16 and designed to swing inwardly in opening. The frame overlaps the outer walls of the port and is shown inclined slightly from a vertical plane so that the valve, by gravity, will swing to its closed position against the frame. The arrangement of the valves within the ports 14^z are such that the frames carrying the valves can be readily withdrawn when the retaining means which hold the frames in position are removed. As a preferred retaining means we have shown wedges 17 which are inserted on each side of each valve frame and on one side engage the frame and on the other side an undercut inclined lug 18. As seen in Figs. 2 and 7, these wedges 17 can be readily withdrawn upwardly, thereby releasing the frames 16 and permitting them and the valves carried thereby to be swung outwardly so that the valves clear the port walls, whereupon the frames and valves can be withdrawn and the valve repaired or substituted. As shown the bottom wall 14^x of the plunger is depressed below each port 14^z, the object of this being to increase the area of the port and to set the valve deeper in the water in the tank. As seen in Figs. 2 and 7, the plunger is designed with four of these depressed portions and four ports, the latter being preferably equi-distantly disposed about the center of the plunger.

60 A packing ring 19 is provided to hold the packing 20 in position between the offset upper end of the plunger 14 and the cylinder 13^x. This ring is secured by means of bolts 21 carried by the plunger 14 and arranged 95 to enter slots 19^x in the ring 19 (see Fig. 3).

The top of the ring 19 is curved inwardly to provide room for nuts 22.

Disposed about the eccentric is a casing like that shown at 23 in Fig. 4. This casing is provided with openings 24 for the shaft 3. The lower part of the casing is provided with flanges 23^x arranged to be bolted to the bottom 14^x of the plunger as shown in Fig. 2. A wrist pin 25 is secured to the lower extensions 23^y of the eccentric casing 23. The arm 26 of the eccentric is journaled on the wrist pin 25 and is integral with the eccentric strap 10.

In Fig. 5 we have shown a modified form of the wrist pin bearing in which the pin 25^a 80 enters a recess 23^c in the casing 23. The head 25^b of the pin is held in place by means of a screw cap 27. The pin is prevented from turning by means of a key 28.

In Fig. 8 we have shown a modified form 85 of casing in which the lower end of the crank case 23 is continued and forms an oil well 23^k which projects through an opening 14^k in the bottom 14^x. In this modified form the flanges 23^x are secured to the bottom in 90 the same manner as that shown in Fig. 2.

It is not necessary to drop the oil receptacle 14^y below the top level of the plunger, though this construction is desirable to shorten the length of the eccentric arm. As 95 a matter of fact, the essential feature of the oiling system is that the eccentric or the equivalent drive means should be inclosed within an oil containing chamber which reciprocates with the plunger and the manner of connecting it to the plunger is therefore not material, and certain important advantages would be obtained even where the design does not extend the well to include the wrist pin. 100

From the foregoing description of the various parts of the device the operation thereof may be readily understood. 105

The interior of the crank case is filled with oil approximately up to the line 0—0 in Fig. 2. The oil may be introduced through the closure. As the drive shaft 3 is turned the plunger will be reciprocated. It will be seen that the working parts are virtually submerged in oil and that the friction of the working parts therefore will be reduced to a minimum. The oil is entirely inclosed since the lower part of the crank case forms an oil well. 115

The movement of the eccentric causes the 120 reciprocation of the plunger. On the downward stroke of the plunger the flap valves 15 close and on the up stroke of the plunger they open to admit water. Owing to the position of the valves and the fact that they 125 are fixed to the plunger, it is impossible for an accumulation of water inside the plunger beyond that which it is desirable to have. Consequently the load on the eccentric is less than that possible with any machine in 130

which the valves are not so placed. In Fig. 10 it will be seen that on the down stroke of the plunger the water is forced upwardly through the stationary screen 25 upon which 5 gold or other material to be treated is placed. The lighter particles are lifted to the top and the heavier particles settle upon the bottom of the screen or perforated plate 25 from whence they are removed through the 10 discharge chute 27.

The main features of our invention, as stated above, relate to the construction of the plunger and the means for lubricating the oscillating mechanism. Water is supplied to the interior of the plunger by means of an inlet pipe 28. The construction of the plunger permits the water to pass through the plunger and hence prevents the back suction which would occur unless the water 20 should pass through the plunger on the up stroke. This renders the device more uniform in its action than in those machines in which the plungers tend to force the water through the screen and then to draw it back 25 on the up stroke.

The fact that the valves are carried by the plunger instead of being underneath or above the plunger also tends to the efficiency of the machine, since where the plunger is 30 solid and has to raise a heavy load of water the power required to return the device is considerably greater than that necessary in our device.

The positions of the valves or doors is at 35 that portion of the tank where the water is cleanest and freest from grit. The absence of grit also tends to prolong the life of the valves thereby necessitating much less cost in time, labor and materials in repairing or 40 replacing them.

We prefer to incline the ported walls outwardly as it facilitates the removal of the valve frames, but the frames can be set vertically or at an angle inwardly and operate 45 with equal effectiveness. By designing the valves and their supporting frames so that the latter can be removed from above and without removing the piston, we have greatly simplified the maintenance and repair cost of the only delicate part of the jigg- 50 ing mechanism.

We prefer to use the circular plunger working in a cylinder but the cross sectional design of the plunger and cylinder may be 55 variously modified and when we refer to the cylinder we mean to include any design of plunger chamber or compartment in which the reciprocating plunger works.

We claim:

60 1. In a jiggling machine, a plunger, a casing in which the plunger moves, means to reciprocate the plunger comprising an arm which is pivoted thereto, and an oil containing casing carried by the plunger and inclos- 65 ing said arm.

2. In a jiggling machine, a cylinder, a vertically reciprocating plunger therefor, overhead means for reciprocating the plunger comprising a drive shaft and an arm pivoted to the plunger and eccentrically connected to 70 said shaft, and an oil containing casing inclosing the arm and its connections to both shaft and plunger and movable with the latter, said movable casing having an opening to receive said shaft.

3. In a jiggling machine, a cylinder, a plunger or piston therefor, a drive shaft, an eccentric connected with said plunger for operating the latter, and an oil reservoir which travels with the plunger and incloses 80 said eccentric, said reservoir forming an oil housing which has side openings to receive the drive shaft.

4. In a jiggling machine, a cylinder, a plunger or piston therefor, a drive shaft, an eccentric connected with said plunger for operating the latter, an oil well carried by said plunger, and a casing for said eccentric, said casing forming together with the oil well an oil housing.

5. In a jiggling machine, a plunger compartment, a plunger therein having ports in its bottom, means to reciprocate the plunger, and valve means carried by the plunger and which, on the down stroke thereof, seal said 95 ports, said means being removable from the top side of the plunger.

6. In a jiggling machine, a plunger compartment, a plunger which reciprocates therein and has a series of openings in its 100 bottom, a vertically removable frame surrounding each opening, and flap valves carried by and adapted to seat against said frames and removable therewith.

7. In a jiggling machine, a cylinder, a plunger carried thereby, said plunger having a series of openings in its bottom, means for reciprocating the plunger, a frame disposed adjacent each opening, a pivoted flap valve carried by each frame, and means for detachably securing the frames to the 105 plunger.

8. In a jiggling machine, a cylinder, a plunger carried thereby, said plunger having a series of openings in its bottom, means for reciprocating the plunger, a frame disposed adjacent each opening, a pivoted flap valve carried by the frame, means for securing the frame in position, said means comprising lugs carried by the bottom of the 110 plunger, and wedges disposed between the lugs and arranged to bear against the frame.

9. In a jiggling machine, a water tank, a cylinder open at both ends, one end of said cylinder projecting into the water in said tank, a hollow plunger disposed within said cylinder, valves carried by said hollow plunger and arranged to close on the downward movement of the plunger and to open on the upward movement, means for admit- 115 120 125 130

ting water into said hollow plunger, and means for reciprocating said plunger.

10. In a jigging machine, a water tank, a cylinder open at both ends, one end of said cylinder projecting into the water in said tank, a hollow plunger disposed within said cylinder, valves carried by said hollow plunger and arranged to close on the downward movement of the plunger and to open on the upward movement, means for admitting water into said hollow plunger, means for reciprocating said plunger, said last named means comprising a shaft, a housing carried by said plunger, and a driving connection between the shaft and plunger which is disposed in said housing, said housing constituting an oil reservoir enclosed except where pierced by said shaft.
11. In a jigging machine, a plunger compartment, a plunger therein, means to reciprocate the plunger, an open bottom chamber formed in the under side of said plunger and having ports in its side walls or the passage of water through the plunger, and inwardly opening flap valves hinged at their upper ends to the plunger and adapted to close said ports on the plunger's down stroke.
12. In a jigging machine, a plunger compartment, a plunger therein, means to reciprocate the plunger, a wall forming part of the bottom of the plunger and disposed at an angle to the horizontal bottom plane of the plunger, there being a series of ports in said wall, and flap valves which are hinged at their upper ends to the plunger

and arranged to close said ports on the plunger's down stroke.

13. In a jigging machine, a plunger compartment, a plunger therein, means to reciprocate the plunger, said plunger being hollow and having its bottom raised at the center to form a water chamber having its inner wall substantially upright, there being a port in said inner wall, and a flap valve on the plunger arranged to close said port on the plunger's down stroke.

14. In a jigging machine, a plunger compartment, a plunger therein, means to reciprocate the plunger, said plunger being hollow and having its bottom raised at the center to form an annular water chamber having its inner wall inclined upwardly and outwardly, there being a series of ports in said inner wall, and flap valves on the plunger arranged to swing by gravity and close said ports.

15. In a jigging machine, a plunger compartment, a plunger therein, means to reciprocate the plunger, said plunger being hollow and having in its bottom a series of spaced water pockets having upright inwardly facing ported walls, and valves for closing said ports which are hinged to said plunger and arranged to swing inwardly and upwardly in opening said ports.
